CUT, A CORPORATION OF WEST VIRGINIA.

BRAKE FOR TALKING-MACHINES.

1,221,285.

Specification of Letters Patent.

Patented Apr. 3, 1917.

Application filed January 30, 1911. Serial No. 806,965.

To all whom it may concern:

Be it known that we, GUADALUPE BUELNA and ARTHUR E. BURSON, citizens of the United States, residing at Santa Barbara, in the county of Santa Barbara and State of California, have invented a certain new and useful Brake for Talking-Machines, of which the following is a specification.

This invention relates to automatic stop mechanism, and more particularly to an automatic stop mechanism especially designed for a talking machine, which ordinarily has a rotating record support or member and a reproducing member, as a sound-box and tone-arm, said record member and reproducing member being relatively movable, the latter being commonly fed relatively to the former by the coaction of the sound-box with the record groove.

20. Heretofore automatic stop mechanisms for talking machines have been devised which necessitated the manual manipulation of some adjustable element, in order that the stop mechanism might become operative at a desired and predetermined point in the operation of the machine, as at the completion of the reproduction of the sound-record. Such manual manipulation of the adjustable element became necessary with each different record reproduced, because of the fact that different records terminate at different distances from the centers of the tablets. It is an object of this invention to entirely do away with the necessity of any manual manipulation of parts of the mechanism, in order that the machine shall stop at the desired time.

30

Another type of automatic stop mechanism for talking machines has been devised wherein the stopping of the machine depends upon certain elements of such mechanism passing through a predetermined cycle of operation, subsequent to the arrival by the machine at the point where it is desired that stopping shall occur.

40

It is a further object of this invention to provide a stop mechanism that shall become operative immediately upon such desired point being reached, as at the completion of the reproduction of the sound-record, without the delay incident to elements passing through a prior cycle of operations.

A further object of this invention is to provide an automatic stop mechanism for talking machines wherein such mechanism is controlled by the relative movement of the sound-record member and the sound-reproducing member, is the tone-arm. In the preferred embodiment to be described the actuation of the stop mechanism is determined by the cessation of movement of the sound-reproducing member transversely of the record member. It is, however, an object of this invention to provide a stop mechanism that shall obtain such actuation of the stop mechanism upon a material variation in the speed of travel of the relatively movable member such, for example, as a material decrease in its speed of movement.

A further object of this invention is to provide an automatic brake for talking machines that shall require no manual manipulation of parts, in order that the machine shall stop at the desired time; that shall operate immediately at the desired point in the operation of the machine without waiting upon a prior cycle of operations; and that shall be controlled by the relative movement of the sound-record member and the sound-reproducing member, being actuated by the cessation of movement of the relatively movable member, or by a material variation in its speed of movement.

A still further object of this invention is to provide a start-and-stop mechanism which shall be automatically actuated to start the rotation of the sound-record tablet, upon movement of the sound-reproducing member to a position adjacent the beginning of the record.

Stated somewhat generally, the invention consists in providing a rotary record support or member having a record tablet thereon, which together constitute a rotating member, and a reproducing member comprising a tone-arm and sound-box, which are normally propelled across the record by the coaction of the sound-box and record groove, and which together constitute a traveling member, in combination with a stop mechanism which is automatically controlled by the movement of said reproducing member. This stop mechanism comprises an element moved by the motor of the machine, herein

shown as a reciprocating device fed by a threaded device that is in turn driven from the record member, and an element moved by the sound-reproducing member, herein shown as an arm swung by the movement of such member, these elements being so constructed and related that, during the advance of the reproducing member across the record member, they coöperate to maintain the stop mechanism inoperative, but that, upon the cessation of movement of the reproducing member, there shall be a differential or relative movement between these elements to cause the actuation of the stop mechanism. It will be apparent, however, that the same operation may result upon a material variation in the speed of lateral movement of the reproducing member such, for example, as a material decrease in the speed of such movement.

The invention is susceptible of embodiment in a variety of mechanical forms, one of which, for the purpose of illustration, has been selected and described with considerable particularity in the accompanying description, but it is to be expressly understood that such embodiment of the invention is for purposes of illustration only, and is not designed as a definition of the invention, reference being had to the accompanying claims for this purpose.

Referring to the drawings, wherein the same characters of reference designate corresponding parts in the several figures,—

Fig. 1 is a fragmentary plan view of a talking machine with the stop mechanism of this invention applied;

Fig. 2 is an enlarged sectional elevation of the brake element and its support;

Fig. 3 is a plan view of the stop mechanism;

Fig. 4 is a fragmentary plan view with the swinging arm removed to illustrate the setting mechanism;

Fig. 5 is a fragmentary side elevation, partly in section, showing the setting mechanism;

Fig. 6 is a section on the line X⁶—X⁶ of Fig. 4, showing the relation of the parts of the stop mechanism after the same has been actuated; and

Fig. 7 is a side elevation of the stop mechanism showing the parts in their normal relation during the lateral traverse of the record tablet by the sound-reproducing member.

Referring in detail to the drawings, wherein the same reference characters indicate corresponding parts in the several figures, 1 represents the casing of the usual or any conventional talking machine, 2 the turn-table driven by a motor (not shown) within the casing 1, and 3 any conventional disk sound-record tablet supported upon and rotated by the turn-table 2, the turn-table and

tablet constituting a rotating member. Above and adapted to coöperate with the record tablet is a reproducing member, shown as comprising the usual or any conventional sound-box 4 communicating with 70 and carried by the usual tone-arm 5, which together constitute a traveling member. The tone-arm is rotatably mounted in any usual or conventional way upon a bracket 6 in communication with a sound-amplifier, as indicated in dotted lines in Fig. 1, the reproducing member being normally progressed across the record tablet by the coaction between the sound-box and the record groove. 75

Mounted upon the bracket 6, in any desired or suitable way, is a supporting member 7, preferably in the form of a bent rod, carrying at its upper end the plate-like member or table 8. Extending through this table 8 at about the central portion thereof is a pivot pin 9. Mounted upon the table 8 and secured in pivotal relation therewith by the pivot pin 9 is the T-shaped supporting arm 10 provided at its outer end with upturned flanges 11 and 12. The flange 12 is 90 provided at its upper edge with a horizontally extending ear 13 from which is supported in suspended relation a headed pivot pin 14. The pivot pin 14 is secured in the ear 13 in any conventional way, as by screw-threaded engagement, a lock-nut 15 being provided to securely lock the pin in its proper position. Supported on the head of the pin 14 are two dished disk-shaped members 16 and 17 which embrace at their periphery a brake member 18. This brake member may be in any preferred form, but in the embodiment disclosed consists of an annulus of frictional material, such as rubber, securely clamped and retained in position by the disks 16 and 17. The disks 16 and 17, together with the brake member 18, constitute a rotary brake element freely rotatable upon the pin 14. 95

Also mounted upon the pin 14 above the brake element, is a rotary stop member 19, freely rotatable upon the pin 14, and providing the projecting portion 20 for a purpose hereinafter described. Between the disk 16 and the stop member 19 is a spring 125 member 21 provided with arms which bear at their outer extremities against the dished portion of the disk 17, such spring member being separated from the plate 17 at the center by a washer. This spring member provides a frictional or yielding connection between the stop member 19 and the brake element, whereby they normally rotate as a unit but are capable of independent rotation. 130

Above the stop member 19, on the pin 14, is mounted a worm 22 provided with a flange 23, which may be integral with the worm, and which flange bears upon and rotates with the stop member 19. It is apparent that any desired means may be provided for 135

locking the flange 23 to rotate with the stop member 19. In gear with the worm 22 is a worm-wheel 24 supported on the end of a threaded shaft 25 which has bearings in the flanges 11 and 12.

Also extending between the flanges 11 and 12 is a rod 26. Mounted on the rod 26, to rock and slide thereon, is a pivoted arm or lever 27 provided at 28 with a tooth or threaded member adapted to mesh or engage with the threaded member 25. The lever 27 is extended beyond the tooth 28 to provide the weighting extension 29, and this lever is also extended in the opposite direction from the rod 26 to provide the finger 30. Also mounted upon the rod 26 in pivotal relation therewith is the gravity member 31 comprising inturned flanges 32 and 33, which are received in pivotal relation on opposite ends of the rod 26, and the connecting member 34. Extending from the member 34 and transversely thereto, is the arm 35 provided at its outer extremity with the extension 37 running parallel to the connecting member 34. The extremity of the extension 37 is inclined upward at right angles thereto to provide a cam surface at 38. Also depending from the extension 37 is a lug or stoppin 39 adapted at the proper time to be moved into the path of the projection on the stop member 19 to stop the rotation of the latter.

Mounted on the pin 9 and in pivotal or revoluble relation therewith, is an arm 40, at the outer end of which is a second arm 41 horizontally pivoted on the arm 40 by means of the pivot 42. Depending from the arm 41 is the lug 43 adapted at the proper time to bear on the extension 37 and depress the lug 39. The arm 41 is extended to provide the finger 44, which is adapted at the proper time to bear upon the finger 30 and tilt the lever 27 to raise the tooth 28 out of engagement with the threaded member 25. The arm 41 is also provided with a diagonal slot 45 adapted to receive therein a pin 46 extending upwardly from the upper face of the lever 27. The pin 46 is reduced at the upper portion thereof to provide the shoulder 46', upon which the arm 41 may rest, the pin 46 constituting a trip for the arm 41. Below the pivoted arm 40 is a plate-like member 47 frictionally held in engagement with the arm 40 by the spring member 48. The plate-like member 47 is also mounted in pivotal relation with the pin 9 and is adapted, owing to the frictional connection provided by the spring 48, to move the arm 40 about the axis of the pin 9. Extending from the plate 47 is an arm 49 provided with an upturned forked extremity 50.

Mounted in pivotal relation with the plate 8 is an arm 51 which extends upwardly from the plate 8, then horizontally over the arm 40, through the fork of the extension

50, and then upwardly to provide the extension 52 which is secured to the tone-arm 5 in any suitable way, as by a clamping member 53.

Depending from the plate 47 is an eccentric pin 54 adapted to coat with the forked end 55 of a lever 56 pivoted on the arm 10 at 57. The lever 56 is provided with a down-turned lug 58 adapted to play in a slot formed by the edge of the arm 10 and an extension 59 on the table 8. Surrounding the pivot 57 is a spring 60 which bears at its opposite ends upon the arm 10 and the depending lug 58. The lever 56 is extended to provide a finger 62.

The operation of the device is as follows:

Assuming the tone-arm and sound-box to be at the inner end of the record groove, as shown in Fig. 1, the sound-arm is first moved outwardly to a position adjacent the periphery of the record. Movement of the tone-arm 5 carries with it the rod 51 which, through the forked extremity 50, moves the plate-like member 47 and therewith the pivoted arm 40. Arm 40 carries with it arm 41, which, through the engagement of the edge of the slot 45 with the pin 46, slides the lever 27, which is then tilted by the engagement of fingers 30 and 44 so that tooth 28 is out of engagement with the threaded member 25, along the rod 26, until the lever is restored to initial position. As the tone-arm is moved farther, plate-like member 47 will slip relatively to arm 40. The rotary movement of plate-like member 47 also causes the eccentric pin 54, acting in the slot provided by the forked end 55, to swing the lever 56 about its pivot 57 to the position shown in dotted lines in Fig. 4, forcing the finger 62 into contact with the cam surface 38. The parts are so timed that finger 62 will not engage cam surface 38 until lever 27 has been restored to initial position. The camming action produced by the finger 62 on the surface 38 causes the arm 35, and therewith the lug 39, to be raised, and the extension 37 of the arm 35, bearing on the lug 43, raises arm 41 above the shoulder 46'. When the arm 41 is thus raised, finger 44 is withdrawn from finger 30, permitting lever 27 to tilt, because of the weighting extension 29, until tooth 28 engages threaded member 25, in which position it is ready to be driven thereby. Upon further movement of the lever 56, the depending lug 58 engages the extension 59, and operates thereon as a fulcrum, the lever 56 then moving, through its pivot 57, the arm 10 about its pivot 9 against the tension of the spring 60, and withdrawing thereby the arm 10 and its supported members, including the brake element, from the position shown in Fig. 1 to a position wherein the brake element is out of engagement with the turn-table.

The sound-box being then placed in opera-

5 tive relation with the record, it begins to travel inwardly through the coaction of its usual needle with the record groove. Movement of the tone-arm inwardly moves the 10 rod 51, and thereby, through the extension 49, the plate-like member 47 is rotated about its pivot 9, causing the eccentric pin 54 to move toward the central portion of the slot formed by the fork 55, permitting lever 56 15 to follow. The first result of this movement is that the arm 10 is permitted to be swung about its pivot 9, through the force exerted by the spring 60, to bring the arm 10 and its supported members into normal 20 working relation with the turn-table, whereby the brake element is brought into frictional engagement with the periphery of the turn-table and thereupon begins to rotate, lug 39 being then held out of the path 25 of projecting portion 20 by finger 62 bearing on cam surface 38. Rotation of the brake element produces a rotation of the worm 22 which, through worm-wheel 24, drives the threaded member 25. Threaded member 25 and its driving mechanism are so designed 30 as to drive lever 27 approximately synchronously with the movement of the arm 41 by tone-arm 5, any difference in speed being in favor of the arm 41, so as to insure that the 35 edge of slot 45 shall be held against the reduced extension of pin 46. When the threaded member begins to rotate, it feeds lever 27, and thereby pin 46, longitudinally, and arm 41, which has been held stationary 40 relatively to the lever 27 by engagement with the pin 46, with a resultant slipping between arm 40 and plate-like member 47, now begins to keep pace with the pin 46, because the tone-arm tends always to drive 45 the arms 40 and 41, through the frictional connection between arm 40 and plate-like member 47, at approximately the same rate of movement and at least at as great a speed as that at which it is advanced by the record 50 groove. The further movement of the tone-arm inwardly permits a further swing of the lever 56, whereby the finger 62 is withdrawn from engagement with the cam surface 38. Arm 35 with its extension 37 is 55 thereby permitted to drop, and arm 41 is correspondingly lowered until the edge of slot 45 rests on the shoulder 46' of pin 46. The lug 39 will not, however, fall into the path of the projecting portion 20, as the arm 60 35 is over-weighted by the connecting member 34, whereby the gravity member 31 normally swings about the rod 26 to maintain the lug 39 elevated. As the tone-arm continues to swing inwardly arms 40 and 41 65 move therewith, the edge of the diagonal slot 45 is held against the reduced extension of the pin 46 projecting therethrough, and the arm 41 is supported on the shoulder 46'. The arm 41 and the lever 27 with its pin 46 now move as a unit, until the tone-arm ceases 70 to advance for any reason, as when it has reached the end of the record groove. Arm 41 then also ceases further movement, and the brake element, being still in contact with and rotated by the turn-table, continues to 75 drive the threaded member 25, whereby the lever 27 is further advanced and shoulder 46' is withdrawn from under the edge of the slot 45. Thereupon arm 41 falls through gravity, its finger 44 engaging the finger 30 80 and raising the tooth 28 out of contact with the threaded member 25, and its lug 43 pressing down upon the extension 37 and overcoming the weight of the member 31, whereby the lug 39 is forced down into the 85 path of the projecting portion 20 of the rotary stop member 19, stopping further rotation of this member. Thereupon the rotary brake element immediately produces a retarding and braking action upon the turn-table, the frictional connection between the brake element and the stop member 19 permitting a slight slipping between the brake element and the stop member, until the turn-table, and thereby the motor, is brought to a 90 stop, the provision of this frictional connection preventing injurious jars. 95

100 It will be apparent that a material variation in the speed of advance of the tone-arm, such as a material decrease in its speed of advance, will similarly decrease the speed of advance of the arm 41, whereby pin 46 with its shoulder 46' will be advanced out from under the edge of the slot 45 to cause the actuation of the brake element as above described. It will also be apparent from the above detailed description that a stop mechanism has been provided which is controlled by the movement of the tone-arm without the necessity of prior manual manipulation 105 of adjustable parts, and which operates immediately upon the cessation of movement of the tone-arm to effect the stopping of the machine.

110 While the preferred embodiment has been described with considerable particularity, it is to be expressly understood that such embodiment is for purposes of illustration only, that the invention is susceptible of a variety of mechanical expressions, some of which 115 will readily suggest themselves to those skilled in the art, and that such embodiment is not intended as a limitation of the scope of the invention, reference being had to the appended claims as a definition of the scope 120 thereof.

125 What we claim is:

1. In combination, a rotating member and a traveling member, a rotating brake element, a stop for said brake element, means to hold said brake stop inoperative, and means controlled by said brake element to actuate said stop when movement of the traveling member has ceased.
2. In combination, a rotating member and 130

a traveling member, a rotary brake element rotated by said rotating member, and means to maintain said brake element inoperative, said means being controllable by said brake element to stop said brake element.

5. In combination, a rotating member and a traveling member, a rotary brake element, a stop for said element, and means controllable by said brake element for actuating said stop when said traveling member has ceased to move.

10. In combination, a rotating member and a traveling member, a brake element arranged to be rotated by said rotating member, and means to stop the rotation of said brake element when the traveling member has ceased to move, said means being controllable by said brake element.

15. In combination, a rotating member and a traveling member, a brake element arranged to be rotated by said rotating member, a stop for said brake element, means to actuate said stop, and means to hold said stop-actuating means in inoperative position, said means being controllable by said brake element to operate said stop-actuating means when the traveling member has ceased to move.

20. In combination, a rotating member and a traveling member, a brake element arranged to be rotated by said rotating member, and means acting when the traveling member ceases to move to stop the rotation of said brake element.

25. In combination, a rotating member and a traveling member, a brake element, and means cooperating with said brake element and acting when the traveling member stops to render operative said brake element.

30. In combination, a rotating member and a traveling member, a brake element arranged to be rotated by said rotating member, a stop for said brake element, means controllable by said traveling member, and means controllable by said brake element to maintain said stop inoperative during the movement of said traveling member, said means controllable by said brake element serving to actuate said stop when the movement of said traveling member has ceased.

35. In combination, a rotating member and a traveling member, a brake element arranged to be rotated by said rotating member, a stop for said brake element, means to actuate said stop, and means to hold said actuating means inoperative during the movement of said traveling member, said holding means being controllable relatively to said actuating means by said brake element when said traveling member has ceased to move.

40. In combination, a rotating member and a traveling member, a brake element arranged to be rotated by said rotating member, a stop for said element, means to actu-

ate said stop, and a trip for said actuating means, said trip being controllable by said brake element after said traveling member has ceased to travel, to trip said stop-actuating means.

45. In combination, a rotating member and a traveling member, a brake element rotatable by said rotating member, means for maintaining said brake element normally inoperative, and means for applying the 70
75
brake upon the cessation of movement of the traveling member.

80. In combination, a rotating member and a traveling member, a brake element rotatable by said rotating member, means to stop the rotation of said brake element, means to hold said stopping means normally inoperative, and means actuating said brake element upon the cessation of movement of the traveling member.

85. In a brake mechanism, the combination with two independently moving members, of a brake member which is mounted to be moved by one of said moving members, and means rendered operative by the stopping of one of said moving members to render said brake member operative to stop the other moving member.

90. In a brake mechanism, the combination of a rotating member and a traveling member, a brake element arranged to be moved by said rotating member, and means to stop the movement of said brake element when the traveling member has ceased to move.

95. In a brake mechanism, the combination of a rotating member and a traveling member, a brake element arranged to be moved by said rotating member, and means to stop the movement of said brake element 100
105
when the traveling member has ceased to move, said means being controllable by said brake element.

110. In a brake mechanism, the combination of a rotating member and a traveling member, a rotary brake element normally in engagement with said rotating member, and means to prevent rotation of said brake element upon the cessation of movement of said traveling member.

115. In a brake mechanism, the combination of two independently moving members, and rotary means rendered inoperative by the stopping of one of said moving members to stop the other moving member.

120. In a brake mechanism, the combination of two independently moving members, of a brake member which is mounted to engage and move with one of said moving members, and means rendered operative by 125
the stopping of one of said moving members to immobilize said brake member to stop the other moving member.

125. In a brake mechanism, the combination of a rotating member and a traveling member,

- member, a brake device, and means controllable by said brake device for rendering said brake device operative.
20. In combination, a rotating member and a traveling member, an element moving with said traveling member, a pivoted lever associated with said element, a screw imparting movement thereto, and a stop mechanism, said element and pivoted lever moving relatively to actuate said stop mechanism.
21. In combination, a rotating member and a traveling member, an element moving with said traveling member, a pivoted member associated with said element, a screw imparting movement thereto, and a stop mechanism, said element and pivoted member moving relatively to stop said rotating member.
22. In combination, a rotating member and a traveling member, an element moving with said traveling member, a pivoted member associated with said element, means imparting movement to said pivoted member, and a stop mechanism, said element and pivoted member moving relatively to stop said rotating member.
23. The combination, with a rotating element and a traveling element, of a brake device adapted to contact with one of said elements, a stop for said device, and means for actuating said stop to immobilize said brake device when one of said elements has ceased to move.
24. The combination, with a rotating element and a traveling element, of a brake device adapted to contact with said rotating element, a stop for said device, and means for actuating said stop to immobilize said brake device when one of said elements has ceased to move.
25. In a device of the character described, the combination of a rotating element, a traveling element, a brake device adapted to contact with said rotating element, a stop for said device, and means for actuating said stop to immobilize said brake device when said traveling element has ceased to travel.
26. The combination with two independently moving members, of a stop member which is mounted to be moved by one of said moving members, and means rendered operative by the stopping of one of said moving members to render said stop member immediately operative to stop the other moving member.
27. The combination with a rotating member and a traveling member, of an arm movable with said traveling member, a revoluble element associated with said arm and engaging said rotating member, and means rendered operative by the stopping of said traveling member to cause said revoluble element to stop said rotating member.
28. The combination with a rotating member and a traveling member, of a pivotally mounted arm movable with said traveling member, a revoluble element associated with said arm and engaging said rotating member, and means rendered operative by the stopping of said traveling member to cause said revoluble element to stop said rotating member.
29. In combination, a rotating member and a traveling member, a revoluble element movable with said traveling member, and means rendered operative to stop said rotating member upon the stopping of said revoluble element.
30. The combination with a rotating member and a traveling member propelled thereby, of stopping mechanism for the rotating member continuously controlled and maintained inoperative by the traveling member while in motion and automatically becoming immediately operative upon the stopping of the traveling member.
31. The combination with a rotating member and a traveling member propelled thereby, of normally inoperative stopping mechanism for the rotating member comprising two associated elements movable by the said rotating and traveling members respectively, the said mechanism automatically becoming immediately operative upon the stopping of the element movable with the traveling member.
32. The combination with a rotating member and a traveling member propelled thereby, of stopping mechanism for the rotating member comprising two elements normally moving in continuous engagement with each other and separately actuated by the said rotating and traveling members respectively.
33. The combination with a rotating member and a traveling member propelled thereby, of stopping mechanism for the rotating member comprising an element movable thereby and an element movable with the traveling member and while so moving continuously engaging the first said element to maintain the stopping mechanism inoperative.
34. The combination with a rotating member and a traveling member propelled thereby, of stop mechanism for the rotating member comprising two elements normally moving in continuous engagement with each other, one actuated by the said rotating member and the other actuated by the traveling member through a yieldable connection.
35. The combination with a rotating member and a traveling member propelled thereby, of a stop device and controlling means therefor comprising two movable elements one of which is adapted to cause the stop device to operate and the other of which normally engages the first to render the stop device inoperative, an actuating connection

- between the traveling member and the first said element, and an actuating connection between the rotating member and the second said element.
36. The combination with a motor, a motor-driven rotating member and a traveling member normally propelled by the rotating member, of a motor-actuated stop device and motor-actuated controlling means for the stop device serving to automatically stop the rotating member upon the stopping of the traveling member and to permit the starting of the rotating member upon movement of the traveling member to a position adjacent the periphery of the rotating member.
37. The combination with a rotating member and a traveling member propelled thereby, of a stop mechanism for the rotating member continuously controlled and maintained inoperative by the traveling member while moving at normal speed and automatically becoming immediately operative upon a predetermined variation of the speed of the traveling member from the said normal speed.
38. The combination with a rotating member and a traveling member propelled thereby, of normally inoperative stopping mechanism for the rotating member comprising two associated elements movable by the said rotating and traveling members respectively, the said mechanism automatically becoming immediately operative upon a predetermined variation of the speed of the element movable with the traveling member.
39. In combination with a rotating member and a traveling member propelled thereby, of a brake for the rotating member, and means whereby the brake becomes operative upon a predetermined variation in speed of one of said members.
40. In combination with a rotating member and a traveling member propelled thereby, of a brake for the rotating member, and means whereby the brake becomes operative upon a predetermined decrease in speed of one of said members.
41. In combination with a rotating member and a traveling member propelled thereby, of a brake for the rotating member, and means whereby the brake becomes operative upon the stopping of one of said members.
42. In combination with a rotating member and a traveling member propelled thereby, of a brake for the rotating member, and means whereby the brake becomes operative upon a predetermined variation in speed of said traveling member.
43. In combination with a rotating member and a traveling member propelled thereby, of a brake for the rotating member, and means whereby the brake becomes operative upon a predetermined decrease in speed of said traveling member.
44. In combination with a rotating member and a traveling member propelled thereby, of a brake for the rotating member, and means whereby the brake becomes operative upon the stopping of said traveling member.
45. In combination with a rotating member and a traveling member propelled thereby, of a stop mechanism for the rotating member, and means whereby said stop mechanism becomes immediately operative upon a predetermined variation in speed of one of said members.
46. In combination with a rotating member and a traveling member propelled thereby, of a stop mechanism for the rotating member, and means whereby said stop mechanism becomes immediately operative upon a predetermined decrease in speed of one of said members.
47. In combination with a rotating member and a traveling member propelled thereby, of a stop mechanism for the rotating member, and means whereby said stop mechanism becomes immediately operative upon the stopping of one of said members.
48. In combination with a rotating member and a traveling member propelled thereby, of a stop mechanism for the rotating member, and means whereby said stop mechanism becomes immediately operative upon a predetermined variation in speed of said traveling member.
49. In combination with a rotating member and a traveling member propelled thereby, of a stop mechanism for the rotating member, and means whereby said stop mechanism becomes immediately operative upon a predetermined decrease in speed of said traveling member.
50. In combination with a rotating member and a traveling member propelled thereby, of a stop mechanism for the rotating member, and means whereby said stop mechanism becomes immediately operative upon the stopping of said traveling member.
51. In combination with a rotating sound-record member and a sound-reproducing member co-operating therewith, of a brake for the sound-record member, and means whereby the brake becomes operative upon a predetermined variation in speed of one of said members.
52. In combination with a rotating sound-record member and a sound-reproducing member co-operating therewith, of a brake for the sound-record member, and means whereby the brake becomes operative upon a predetermined decrease in speed of one of said members.
53. In combination with a rotating sound-record member and a sound-reproducing member co-operating therewith, of a brake for the sound-record member, and means whereby the brake becomes operative upon the stopping of one of said members.

54. In combination with a rotating sound-record member and a sound-reproducing member coöperating therewith, of a brake for the sound-record member, and means whereby the brake becomes operative upon a predetermined variation in speed of said reproducing member. 65
55. In combination with a rotating sound-record member and a sound-reproducing member coöperating therewith, of a brake for the sound-record member, and means whereby the brake becomes operative upon a predetermined decrease in speed of said reproducing member. 70
56. In combination with a rotating sound-record member and a sound-reproducing member coöperating therewith, of a brake for the sound-record member, and means whereby the brake becomes operative upon the stopping of said reproducing member. 75
57. In combination with a rotating sound-record member and a sound-reproducing member coöperating therewith, of a stop mechanism for the sound-record member, and means whereby the stop mechanism becomes immediately operative upon a predetermined variation in speed of one of said members. 80
58. In combination with a rotating sound-record member and a sound-reproducing member coöperating therewith, of a stop mechanism for the sound-record member, and means whereby the stop mechanism becomes immediately operative upon a predetermined decrease in speed of one of said members. 85
59. In combination with a rotating sound-record member and a sound-reproducing member coöperating therewith, of a stop mechanism for the sound-record member, and means whereby the stop mechanism becomes immediately operative upon the stopping of one of said members. 90
60. In combination with a rotating sound-record member and a sound-reproducing member coöperating therewith, of a stop mechanism for the sound-record member, and means whereby the stop mechanism becomes immediately operative upon a predetermined variation in speed of said reproducing member. 95
61. In combination with a rotating sound-record member and a sound-reproducing member coöperating therewith, of a stop mechanism for the sound-record member, and means whereby the stop mechanism becomes immediately operative upon a predetermined decrease in speed of said reproducing member. 100
62. In combination with a rotating sound-record member and a sound-reproducing member coöperating therewith, of a stop mechanism for the sound-record member, and means whereby the stop mechanism becomes immediately operative upon the stopping of said reproducing member. 105
- comes immediately operative upon the stopping of said reproducing member. 110
63. The combination with a rotating member and a traveling member normally propelled thereby, of stop mechanism serving automatically to stop the rotating member upon the stopping of the traveling member and to permit the starting of the rotating member upon movement of the traveling member to a position adjacent the periphery of the rotating member. 115
64. The combination with a rotating record member and a sound-reproducing member coöperating therewith, of stop mechanism serving automatically to stop the record member upon the stopping of the reproducing member and to permit the starting of the record member upon movement of the reproducing member to a position adjacent the periphery of the record member. 120
65. The combination of a rotary member and a traveling member normally propelled thereby, of a stop device and means controlled by said traveling element automatically rendering said stop device operative upon the stopping of said traveling member and automatically rendering said stop device inoperative upon movement of said traveling member to a position adjacent the periphery of the record member. 125
66. The combination of a rotary record support and a tone-arm coöperating therewith, of a stop device and means moved by said tone-arm automatically rendering said stop device operative upon the stopping of said tone-arm and automatically rendering said stop device inoperative upon the movement of said tone-arm to a position adjacent the periphery of said record support. 130
67. In combination with a motor and a traveling member propelled thereby, of a stop device, and means moved by said motor and member respectively and differentially movable to render operative said stop device upon a predetermined variation in the speed of said member. 135
68. In combination with a motor and a traveling member propelled thereby, of a stop device, and means moved by said motor and member respectively and differentially movable to render operative said stop device upon the speed of said member decreasing below a predetermined limit. 140
69. In combination with a motor and a traveling member propelled thereby, of a stop device, and means moved by said motor and member respectively and differentially movable to render operative said stop device upon the stopping of said member. 145
70. The combination with a rotating member and a traveling member propelled thereby, of a stop device and controlling means therefor comprising two normally engaging

- movable elements, and driving connections between said elements and said members respectively, one of said connections comprising frictionally-engaging parts.
71. The combination with a rotating member and a traveling member propelled thereby, of a stop device and controlling means therefor comprising two normally engaging movable elements, and driving connections between said elements and said members respectively, the connection between said traveling member and its driven element comprising frictionally-engaging members.
72. In combination with a motor and a traveling member normally propelled thereby, of a stop device and controlling means therefor comprising a device driven by said motor and a device moved by said traveling element in engagement with said first motor-driven device, said controlling means automatically rendering said stop device operative upon the stopping of said traveling element.
73. In combination with a motor and a traveling member normally propelled thereby, of a stop device and controlling means therefor comprising a threaded member driven by said motor, and coacting means moved by said traveling member.
74. In a brake mechanism, the combination of two independently moving members, and brake means rendered operative by a predetermined variation in speed of one of said moving members.
75. In a brake mechanism, the combination of two independently moving members, and brake means rendered operative by a predetermined decrease in speed of one of said moving members.
76. In a brake mechanism, the combination of two independently moving members, and brake means rendered operative by the stopping of one of said moving members.
77. In a brake mechanism, the combination of two independently moving members, and brake means rendered operative by a predetermined variation in speed of one of said moving members to stop the other moving member.
78. In a brake mechanism, the combination of two independently moving members, and brake means rendered operative by a predetermined decrease in speed of one of said moving members to stop the other moving member.
79. In a brake mechanism, the combination of two independently moving members, and brake means rendered operative by the stopping of one of said moving members to stop the other moving member.

In testimony whereof we affix our signatures in the presence of two witnesses.

GUADALUPE BUELNA.
ARTHUR E. BURSON.
